PRODUCTION OF HYDROCARBON SOLVENTS OF LOW ACID WASH COLOR

Robert M. Love and Richard E. Tannich, Baytown, Tex., assignors, by mesne assignments, to Esso Research and Engineering Company, Elizabeth, N. J., a corporation of Delaware

Application January 28, 1953, Serial No. 333,682

8 Claims. (Cl. 260—668)

The present invention involves a process for producing hydrocarbons having a low acid wash color and involves subjecting a hydrocarbon, which may be a naphthenic hydrocarbon fraction boiling in the range between 200° and 300° F. and containing a small amount of olefins, to hydroforming conditions to form a product having a high acid wash color. The total product from the hydroforming operation is then cooled to a temperature below the hydroforming temperature and is immediately subjected to contact with a hydrogenation catalyst to form a second product without intervening storage. The product from the hydrogenation operation is then distilled to recover fractions boiling in the range between 200° and 300° F. and following the distillation operation subjected to solvent extraction in the presence of a solvent selective for removal of aromatic fractions to form an extract and raffinate phase. The raffinate and extract phases may then be subjected to distillation to recover fractions boiling in the range between 200° and 300° F. having solvent properties and low acid wash colors.

This application is a continuation-in-part of Serial No. 157,094, entitled "Production of Hydrocarbon Solvents," filed April 20, 1950, now abandoned, in the names of Robert M. Love and Richard E. Tannich.

The invention will be further illustrated by reference to the drawing in which

Fig. 1 illustrates a preferred mode of practicing the invention, and

Fig. 2 is a plot of data showing the relationship between acid wash color of one of the solvent fractions and the feed rate of the hydrogenation step at two different temperature levels.

Referring now to the drawing and particularly to Fig. 1, numeral 11 designates a charge line through which a feed stock such as one having the following analysis is introduced from a source not shown.

TABLE I

Boiling range, ° F-----	200-300.
Olefins, percent volume-----	Less than 1.0.
Aromatics, percent volume-----	5-15.
Paraffins, percent volume-----	35-55.
Naphthenes, percent volume-----	40-50.

A feed stock having the composition indicated in Table I is passed through line 11 through a heating unit or heat exchanger 12 wherein its temperature is raised to a hydroforming temperature, for example a preferred temperature in the range between 850° and 1100° F. and then discharged by line 13 into a hydroforming zone generally indicated as 14, which will comprise hydroforming reactors and other auxiliary equipment as well known to the art. The average reaction temperature in the hydroforming zone is preferably in the range between 925° and 950° F. Hydrogen is introduced into hydroforming zone 14 by line 15 in an amount sufficient for the reaction and usually approximately 2000 cu. ft. per barrel of feed. Hydroforming zone 14 is a catalytic hydroforming zone and a suitable hydroforming catalyst such as an oxide of

chromium, molybdenum or vanadium supported on a suitable support such as alumina or zinc spinel, is provided for contact with the hydrogen and the feed mixture. The feed charged to hydroforming zone 14 by line 13 may be routed therethrough at a space velocity of 1.0 volume of feed per volume of catalyst per hour and at the temperatures obtaining and at a preferred pressure of 215 p. s. i. g. causing the naphthenes in the feed to be converted to aromatics. The operation in hydroforming zone 14 results in the production of a product having a high concentration of aromatics, but having a relatively high concentration of components such as cyclopentadienes and the like which cause solvents produced therefrom as described below to have a high acid wash color as determined by the ASTM test method D848.47. This high acid wash color product is discharged from zone 14 by line 16 and passes through heat exchanger or cooler 17 wherein its temperature is reduced to a temperature below 700° F. which may suitably be in the range between 550° and 700° F. with a preferred temperature of 600° to 650° F.; the effluent vapor from cooler or heat exchanger 17 discharges immediately by line 18 into a hydrogenation zone 19 without intervening or intermediate storage between the hydroforming operation, the cooling step, and the hydrogenation zone. The time elapsed between hydroforming zone 14 and hydrogenation zone 19 is in the range between 0.1 and 100 seconds and usually will be about 1 to 10 seconds. Good results may be obtained when the time between zones 14 and 19 is within the range between 1 and 60 seconds. Zone 19 is shown as a block in the flow diagram which will be understood to include a catalytic hydrogenation reactor and all auxiliary facilities therefor which are well known to the art. The total product from zone 14, including unreacted hydrogen and the unreacted feed and the reacted products, thus pass immediately and directly into hydrogenation zone 19 at a temperature such as set out before, no extraneously added hydrogen being added. Under these conditions the acid wash color forming components which may include cyclopentadienes which polymerize on storage are removed or converted to harmless compounds. It is believed that the "bad actors" are principally diolefins which are contained in the product from hydroforming zone 14 and which are saturated to form paraffins or mono-olefins, resulting in a drastic lowering of the acid wash color of the solvents subsequently produced.

It is important that the product from hydroforming zone 14 be routed directly and immediately to the hydrogenation zone 19 within the time specified including the time for adjusting the temperatures to the desired point for hydrogenation. If the hydroformed product is condensed and allowed to remain in storage for an appreciable length of time the diolefins including cyclopentadiene and/or its homologues are polymerized to undesirable acid wash color producing bodies and are not affected by subsequent hydrogenation treatment. In short, the advantages of the present invention are realized by hydrogenation of the hydroformed product immediately after the hydroforming operation. The catalyst provided in hydrogenation zone 19 may be a mixture of nickel and tungsten sulfides or other hydrogenation catalysts having equivalent or superior hydrogenating activity, such as platinum, Raney nickel, cobalt molybdate and the like. It has been found that other catalysts of lesser activity, for example, catalysts which require higher temperatures to accomplish the desired degree of hydrogenation, while working the same amount of bromine number reduction, do not allow the obtaining of a reduced acid wash color. Therefore, it is important that the catalysts employed in hydrogenation zone 19 be capable of hydrogenating at a temperature below about 700° F.

The product from hydrogenation zone 19 discharges therefrom by line 20 into a second cooler or heat exchanger 21 wherein the temperature is further reduced and the cooled product discharged by line 22 into a separator 23 wherein unreacted hydrogen and low boiling hydrocarbons are removed by line 24 for recycling to the hydroforming zone. The separated liquid product is discharged from separator 23 by line 25 into a first distillation zone 26 which is provided with a heating means indicated by coil 27 whereby temperatures in zone 26 are adjusted to allow obtaining overhead by line 28 hydrocarbons, including butanes, boiling up to 200° F., which may be used in the production of motor fuel, if desired, while a fraction largely boiling between 200° and 300° F. and including some heavier fractions formed in the two reactions is withdrawn from zone 26 by line 29 and introduced thereby into a second distillation zone 30 which, similar to distillation zone 26, is provided with heating means illustrated by coil 31 for adjustment of conditions therein for removal of various fractions desired.

It will be understood that distillation zones 26 and 30 are provided with the usual vapor and liquid contacting equipment well known to the art, such as bell cap trays, Raschig rings and other packing equipment which is commercially available and allows intimate contact between vapors and liquids.

Conditions are adjusted in fractionation zone 30 to remove overhead a fraction which may boil in the range between 200° and 300° F. by line 32, while any heavier fractions produced in hydroforming zone 14 or in hydrogenation zone 19 may be discharged from the system by line 33 for further use as may be desired.

Under some conditions it may be desirable to take overhead by line 32 a fraction of 205°-245° F. boiling range which will comprise substantially toluene and withdraw a second fraction as a side stream from distillation zone 30 by line 34 controlled by valve 35 which may have a 255°-300° F. boiling range and comprise substantially xylenes. A still third fraction may be withdrawn from distillation zone 30 including aromatic hydrocarbons having 9 and 10 carbon atoms in the molecule, by line 36 controlled by valve 37.

The fraction withdrawn from distillation zone 30 by line 34 may be treated in a similar manner to that withdrawn by line 32. For purposes of simplifying the discussion it will be assumed that the fraction withdrawn by line 32 boils in the range between 200° and 300° F., but it is to be clearly understood that this may be a substantially toluene fraction or that the xylene fraction may be substituted therefor or, preferably, both fractions may be recovered for subsequent treatment and/or purification as will be described. In any event, the fraction withdrawn by line 32 or 34 as the case may be, is discharged into solvent extraction zone 38 which is generally indicated as a block in the flow diagram. Zone 38 will be understood to comprise extraction facilities well known to the art. It will be further understood that solvents having the ability to remove aromatic fractions from predominantly paraffinic fractions may be employed, such as liquid sulfur dioxide, phenol, furfural, nitrobenzene and many others too numerous to mention here. It will also be understood that a wash oil may be used in solvent extraction zone 38, especially when sulfur dioxide is the solvent.

Sulfur dioxide is introduced into solvent extraction zone 38 by line 39, while the wash oil is introduced thereto by line 40. Solvent extraction zone 38, as mentioned before, will comprise the usual extraction towers and other equipment to allow formation of extract and raffinate phases. It will also be understood that zone 38 will include facilities for removing solvent from both extract and raffinate phases.

Depending on the solvent employed in zone 38 the solvent extract zone is operated under suitable conditions of

temperature and pressure and solvent to oil ratios well known to the art to form an extract and raffinate phase, the raffinate being discharged by line 41 and the extract being discharged by line 42 into a distillation zone 43 which, similar to distillation zones 26 and 30, is provided with heating means indicated by coil 44 whereby conditions are adjusted in zone 43 to allow recovery of the various fractions. Distillation zone 43, like distillation zones 26 and 30, will also be provided with suitable internal contacting equipment to obtain intimate contact between liquids and vapors. Conditions may be adjusted in distillation zone 43 to recover a light, intermediate and a relatively heavy aromatic fraction. If the fraction charged by line 32 to zone 38 is the fraction boiling between 200° and 300° F., toluene may be recovered from zone 43 by line 45, while xylenes may be discharged therefrom by line 46 and heavier aromatic fractions, if any, recovered by line 47. The paraffinic wash oil introduced into zone 38 by line 40 which has an initial boiling point above 300° F., may be recovered from zone 43 by line 48 for further use in zone 38.

The raffinate withdrawn from zone 38 by line 41 discharges thereby into distillation zone 49 which, similar to distillation zones 26, 30 and 43, is provided with heating means illustrated by coil 50. Zone 49 is also provided with internal baffling equipment like those of zones 26, 30 and 43. Distillation zone 49 may be provided with a line 51 for recovering overhead a relatively light paraffinic hydrocarbon solvent, an intermediate boiling paraffinic solvent by line 52 and a heavier paraffinic hydrocarbon solvent by line 53. Heavier fractions, if any, may be discharged by line 54.

From the foregoing description taken with the drawing it will be apparent that a simple integrated process is provided wherein solvents may be produced by hydroforming and hydrogenation in which the total product from the hydroforming zone is routed immediately within a time of 0.1 to 100 seconds from the time it leaves the hydroforming zone through the hydrogenation zone, following which the product from the hydrogenation zone is subjected to a series of recovery steps to recover both paraffinic solvents having a low bromine number and low acid wash colors and aromatic solvents having low acid wash colors and bromine numbers.

The conditions obtaining in hydroforming zone 14 will include an average reactor temperature in the range between 850° and 1100° F. with a preferred temperature in the range between 925° and 950° F. The pressures will be in the range from 175 to 500 p. s. i. g. with a preferred pressure of 215 p. s. i. g. The amount of hydrogen employed in hydroforming zone 14 will be in the range from 500 to 5,000 cu. ft. per barrel of feed with about 2,000 cu. ft. of hydrogen per barrel of feed preferred. The catalysts, as mentioned before, may be an oxide of molybdenum, chromium, vanadium on a suitable porous support such as alumina or zinc spinel.

The liquid space velocities obtaining in hydroforming zone 14 may be in the range from 0.5 to 5 volumes of feed per volume of catalyst per hour with a preferred space velocity of 1.0 volume of feed per volume of catalyst per hour.

The term hydroforming is well known in the literature and is well accepted in both the patent and trade literature; for example, hydroforming operations have been described in the literature, for example, in the Oil and Gas Journal, March 27, 1941, page 87, and in the Journal of the Institute of Petroleum, January 1944, pages 3 and 4, and may be characterized as those chemical reactions which take place when hydrocarbon oils, particularly hydrocarbons boiling in the gasoline range, are reacted at a temperature in excess of 500° F. in the presence of hydrogen and a hydroforming catalyst; these reactions involve a net effect of taking hydrogen away from the hydrocarbon molecules. The chemical reactions involved are complex but are generally considered

to consist mainly of dehydrogenation and cyclization, although other reactions, such as cracking, hydrogenation and desulfurization, may also occur.

The conditions employed in hydrogenation zone 19 will include a temperature below 700° F. which may suitably be in the range between 550° and 700° F. with a preferred temperature in the range between 600° and 650° F. Since the hydrogen for the reaction is provided in the product from hydrogenation zone 14 by line 16 the pressures employed in hydrogenation zone 19 will be approximately the same as those obtaining in hydro-forming zone 14 and the amount of hydrogen should also be approximately the same.

As mentioned before, the catalyst employed in zone 19 should be a mixture of sulfides of nickel and tungsten or other hydrogenation catalyst of equivalent or greater hydrogenation activity. As examples may be mentioned Raney nickel, cobalt molybdate, platinum and the like. It has been observed that some of the usual hydrogenation catalysts of lesser activity which require higher reaction temperatures when employed in the hydrogenation stage of the present invention, are not suitable. If catalysts of the latter class are employed, bromine number reduction may be effected but the acid wash color of the solvents produced is not correspondingly reduced.

In order to illustrate the invention further, runs were made wherein a fraction boiling in the range from 100° to 300° F. was hydroformed in a commercial unit. A product was obtained, a portion of which was distilled into fractions. A portion of the total hydroformed product was then hydrogenated at a liquid space velocity of 10 volumes of feed per volume of catalyst per hour at a temperature of 630° F. in the presence of hydrogen to obtain a hydrogenated product, which, similar to the feed, was subjected to fractionation. The following table shows the bromine numbers of the fractions before and after hydrogenation and indicates the fractions containing toluene, xylenes, and heavier solvents.

TABLE II
Bromine number

Cut Point Tap Vapor Temperature	Feed to Hydrogenation	Hydrogenated Product
IBP-110° F.		4.8) suitable for use
110°-150° F.	10.5	5.0) in motor gaso-
150°-205° F.	7.7	5.9) line.
205°-245° F.	4.4	2.7 Toluene.
245°-255° F.	4.3	2.5 Motor gasoline.
255°-300° F.	2.7	1.6 Xylenes.
Bottoms	2.5	0.8 Solvents.

Table II indicates the boiling ranges of the gasoline and solvent fractions recovered. It also shows that the hydrogenation step of our invention permits the retention of appreciable olefins in the fractions going to motor gasoline. This is highly desirable, in view of the well known superior anti-knock qualities of olefins over the corresponding paraffins. It will be shown below that the acid wash color of the finished solvent fractions is remarkably improved in spite of the fact that the hydrogenation is only partial, as shown above.

A toluene concentrate was then recovered from a hydrogenated 205°-245° F. fraction by solvent extraction, and treated with 5 pounds of acid per barrel of toluene. A xylene concentrate was also recovered in a similar manner, but was not subjected to acid treating. Heavier aromatics including C₉ and C₁₀ concentrates were recovered without solvent extraction or acid treatment.

The corresponding fractions from the feed to the hydrogenation unit were submitted to solvent extraction to recover a toluene concentrate, and a xylene concentrate. Heavier aromatic concentrates containing the C₉ and C₁₀ aromatics were not solvent extracted. These fractions, like the hydrogenated fractions, were tested for acid wash

color. Another portion of the feed to the hydrogenation zone was separated into toluene, xylene and C₉ and C₁₀ aromatic fractions and these fractions were recovered similarly and the concentrates treated with 10 pounds of sulfuric acid per barrel.

The aliphatic solvents from the 200° to 300° boiling range raffinate of the extraction steps mentioned before were also separately recovered.

The results of these runs are shown in Table III:

TABLE III

Finished Solvent	Hydrogenated 10 v./v. @ 630° F.	Unhydrogenated Without Acid Treatment	10 lb. H ₂ SO ₄ per bbl.
Toluene:			
Acid wash color	1 0-1	12	6-7
Bromine No.	1 0.2	3.0	0.1
Xylene:			
Acid wash color	3-4	10	4-5
Bromine No.	0.8	1.0	0.1
C ₉ and C ₁₀ :			
Saybolt Color	30	10	-----
Bromine No.	0.4	1.4	-----
Aliphatic Solvents (From raft):			
Bromine No.	0.8	3.0	-----

¹ After treat with 5 lb. H₂SO₄ per bbl.

The acid wash color of the toluene before acid treating was considerably higher and is estimated to be about 5 while the bromine number is estimated to be 1.

It will be noted, comparing the hydrogenated with the unhydrogenated material, that with 5 lb. H₂SO₄ per bbl. it is possible to produce a hydrogenated toluene fraction having an acid wash color in the range from 0-1, whereas the corresponding unhydrogenated fraction without acid treatment had an acid wash color of 12, while with 10 lb. H₂SO₄, the acid wash color was in the range of 6-7. It will be noted that the bromine number of the hydrogenated toluene solvent was 0.2 whereas the bromine number of the unhydrogenated stock treated with 10 lb. H₂SO₄ was 0.1, while for the unhydrogenated fraction without acid treatment the bromine number was 3.0. The xylene fraction produced in accordance with the present invention had a low acid wash color in the range between 3-4, whereas that of unhydrogenated stock treated with 10 lb. H₂SO₄ per bbl. was in the range of 4-5, and without acid treating it had an acid wash color of 10. The bromine number of the xylene fraction produced in the present invention was 0.8, sufficiently low to meet specification.

It is to be especially noted that the C₉ and C₁₀ aromatic solvent had a Saybolt color of 30, whereas that produced without hydrogenation had a Saybolt color of only 10 and the bromine number was 0.4 with and 1.4 without hydrogenation.

The aliphatic solvents produced in accordance with the present invention had a bromine number of 0.8, whereas the unacid treated product which had not been hydrogenated had a bromine number of 3.0. This is considered a significant quality improvement.

In passing, it might be mentioned that ordinarily where hydrogenation is not employed it is necessary to use 15 pounds H₂SO₄ per bbl. to finish the toluene fraction, about 13 pounds H₂SO₄ per bbl. to finish the xylene fraction, and approximately 10 pounds H₂SO₄ per bbl. are required to finish the C₉ and C₁₀ aromatic fractions. Furthermore, the decrease in the olefin content of the paraffinic solvent produces a product of superior quality with respect to gum and peroxide formation and the like.

In order to test the effect of carrying out a process following the operating steps of our invention but employing a different hydrogenation catalyst, runs were made by hydrogenating toluene and xylene fractions from a hydroformate over a hydroforming catalyst consisting of

molybdena supported on alumina, which is known to be a hydrogenation catalyst at proper reaction conditions. The acid wash colors and bromine numbers of the hydrogenated and solvent extracted fractions are recorded in Table IV.

TABLE IV

Hydrogenation:

Conditions	2 v./v./hr. @ 800° F.
Catalyst	MoO ₃ on Al ₂ O ₃
Toluene—	
Acid wash color	6-7
Bromine No.	.9
Xylene—	
Acid wash color	5-6
Bromine No.	.3

The original bromine numbers of the unhydrogenated fractions were substantially those given in Table II, i. e. about 4.4 for the toluene and about 2.7 for the xylene fraction. It is seen that, in these runs, the bromine number reduction of the toluene fraction was about the same as that obtained in the run over nickel-tungsten sulfide hydrogenation catalyst, reported in the first column of Table III, and the bromine number reduction of the xylene fraction was considerably greater. Nevertheless, the acid wash color of each fraction was appreciably higher. Furthermore, it is seen that even this amount of reduction was obtained only under much more severe hydrogenation conditions than we desire to employ in our invention.

Data from runs while hydrogenating a hydrocarbon fraction at 600° and 700° F. at liquid space velocities varying from about 5 to about 45 v./v./hr. were obtained and the acid wash color of the xylene concentrate determined. These runs are presented graphically in Figure II which shows that at 600° F. the curve for the acid wash color plotted against the space velocity reaches a maximum acid wash color at about 45 v./v./hr. and that an acid wash color of about 5 is obtained at about 15 v./v./hr. On the other hand, at 700° F. the acid wash color begins initially at about 5 and rapidly increases to 7 at about 30. In short, the data in Figure II shows that it will be desirable to operate at a temperature in the range between 600° and 650° F. at space velocities from about 8 to 45 v./v./hr. with a preferred space velocity of approximately 10.

In order to show the advantages of the present invention over an operation where the product from a hydroforming zone was stored prior to hydrogenation a run was made in which a product was obtained from a commercial hydroforming unit which was charging a 200° to 300° F. naphthenic hydrocarbon fraction over conventional molybdena-on-alumina hydroforming catalyst under conventional hydroforming conditions of about 930° F. average catalyst bed temperature, 250 p. s. i. g. pressure, a liquid space velocity of 1 v./v./hr., and a recycle gas rate of 2000 standard cubic feet per barrel of feed. A portion of the liquid fraction of this hydroformed product, boiling between approximately 100° and 350° F., was condensed and stored at atmospheric temperature under a nitrogen blanket for a period in excess of two weeks. This fraction was then hydrogenated over a nickel-tungsten sulfide catalyst, which had been on stream for 10 to 12 days; at a temperature of 625° F., a pressure of 190 p. s. i. g., a liquid space velocity of 10 volumes of feed per volume of catalyst per hour, in admixture with a sufficient amount of gas containing approximately 65% hydrogen, and obtained from the recycle gas stream of a commercial hydroforming unit, to provide a hydrogen to oil ratio in the range of 1200 to 1400 standard cubic feet of hydrogen per barrel of oil. The hydrogenated product was condensed and fractionated and the acid wash color of the fraction boiling between 200° and 250° F. was determined and found to be 4 and that of the fraction boiling between 250° and 300° F. was found

to be intermediate between 5 and 6. The xylenes portion of the product was segregated and extracted with liquid SO₂ to eliminate non-aromatics therefrom and the acid wash color of the extracted xylenes was subsequently determined and found to be 5. The bromine number of the feed to the hydrogenation step was 5.8, and that of the total hydrogenation product was 2.5.

In order to illustrate the practice of the present invention a hydrogenation unit was connected into a hydroforming unit in which provision was made to cool the total product of the hydroforming operation without condensation and the total product was routed into a hydrogenation unit. The product from the hydroforming unit was obtained while charging to the hydroforming unit a 200° to 300° F. naphthenic hydrocarbon fraction over conventional molybdena-on-alumina hydroforming catalyst under conditions of about 930° F. average catalyst period temperature 250 lbs. p. s. i. g. liquid space velocity of 1 v./v. per hour and a recycle gas rate of about 2000 standard cubic feet per barrel of feed. The product from the hydroforming operation was obtained in vapor form at the temperature of the hydroformer reactor outlet, including all unconverted feed components, converted fractions, and gases including hydrogen. The temperature of this total product was adjusted without intermediate condensation, and the total product without intermediate or intervening storage was then passed directly over nickel-tungsten sulfide catalyst which had been on stream for 123 days, at a temperature of 623° F., a pressure of 190 lbs. p. s. i. g., and a liquid space velocity of 10 volumes of feed per volume of catalyst per hour. The time between the hydroforming zone, the cooling operation and the entrance into the hydrogenation zone was 2 seconds. In short, the total product from the hydroforming operation contacted the hydroforming catalyst nearly immediately.

The hydrogen to oil ratio in the total product was in the range from 1200 to 1400 standard cubic feet of hydrogen per barrel of oil. The hydrogenated product was condensed and fractionated and the acid wash color of the fraction boiling between 200° and 250° F. was determined and found to be 2, and that of the fraction boiling between 250° and 300° F. was found to be 5. The xylenes portion of the product was segregated and extracted with liquid SO₂ to eliminate non-aromatics therefrom, and the acid wash color of the extracted xylenes was subsequently determined and found to be 4. The bromine number of the feed to the hydrogenation step was 4.6, and that of the total hydrogenated product was 2.4.

Comparing the data of the run where the product from the hydroforming operation was stored and the product from the run where there was no intervening storage and the product was passed immediately into the hydrogenation zone it will be seen that substantially better acid wash color, particularly in the 200° to 250° F. fraction was obtained and that this improvement was obtained in spite of the fact that the hydrogenation catalyst in the run where the practice of the present invention was employed was of greater age than in the run where intervening storage of the product obtained. It is believed that the practice of the present invention results in substantially improved acid wash color because of the fact that cyclopentadiene and/or its homologues are present in the hydroformed product. It is believed that the cyclopentadiene polymerizes on condensation and storage which results in the formation of compounds which contribute to poor acid wash color.

The practice of the present invention, which results in reduction of acid wash color of the hydroformed and hydrogenated product, allows the obtaining of substantial monetary savings since otherwise it would be necessary to treat the hydroformed product with large amounts of acid to obtain the desired acid wash color which the present invention allows. Acid treatment of the hydroformed product results in loss of valuable aromatic compounds which is obviated in the practice of the present invention.

It is believed also that practice of the present invention reduces the concentration of unsaturated compounds which tend to form peroxides upon atmospheric oxidation. Such oxidation products, as exemplified by peroxides, are deleterious in subsequent processing steps such as, for example, solvent extraction with liquid SO₂.

The "Acid Wash Color" test referred to herein, namely ASTM test method D-848-47, may be briefly described as a method of testing industrial aromatic hydrocarbons of relatively high purity by agitating three volumes of the aromatic with one volume of concentrated (96±0.5%) sulfuric acid for 20 seconds, permitting the layers to separate, and comparing the color of the acid with a set of standards, which are numbered from 0 (water white) to 14 (the color of half saturated aqueous K₂CrO₄). The test is an indication of the presence of undesired highly reactive compounds, such as diolefinic materials, which have a tendency to interfere in reactions and processes in which the aromatics may be employed.

The bromine numbers referred to herein were determined by a modified Lewis and Bradstreet method. The numbers are numerically equal to centigrams of bromine consumed per gram of sample.

While the present invention has been described with respect to specific examples, it will be understood that the process may be varied without departing from the spirit and scope of the invention. For example, while the process is particularly applicable to the production of aromatic solvents, it is also applicable to the production of paraffinic solvents and it is specifically contemplated that it may be used for the production of both types of solvents.

The nature and objects of the present invention having been completely described and illustrated, what we desire to claim as new and useful is:

1. A method for producing hydrocarbon solvents having a low acid wash color which comprises the steps of hydroforming a naphthenic hydrocarbon fraction containing a small amount of olefins less than about 2% by volume and boiling in the range between 200° and 300° F. under hydroforming conditions of temperature and pressure in a first zone to convert naphthenes to aromatics and to form a total first vaporous product including unreacted hydrogen, unreacted feed and reacted products having a high concentration of acid wash color forming bodies in the 200° to 300° F. boiling range, reducing the temperature of the total first product to a temperature below 700° F., immediately passing said total vaporous first product at said reduced temperature after said total first product leaves said first zone into a second zone, hydrogenating said total first product in said second zone in the absence of extraneously added hydrogen in the presence of a hydrogenating catalyst selected from the group consisting of nickel-tungsten sulfide, platinum, Raney nickel, and cobalt molybdate at a temperature below 700° F. and at a space velocity higher than a space velocity in said hydroforming step to form a second product having a low concentration of acid wash color forming bodies in the 200° to 300° F. boiling range and distilling said second product to recover a fraction boiling in the range between 200° and 300° F. having solvent properties and an acid wash color not in excess of 6.

2. A method in accordance with claim 1 in which the low acid wash color product is an aromatic hydrocarbon fraction.

3. A method in accordance with claim 1 in which the low acid wash color product is a paraffinic hydrocarbon fraction.

4. A method in accordance with claim 1 in which the low acid wash color product is recovered by distillation followed by solvent extraction at low temperatures with liquefied sulfur dioxide in the presence of a paraffinic wash oil having a boiling point above 300° F.

5. A method for producing hydrocarbon solvents having a low acid wash color which comprises the steps of hydroforming a naphthenic hydrocarbon fraction containing a small amount of olefins less than about 2% by volume and boiling in the range between 200° and 300° F. under hydroforming conditions of temperature and pressure in a first zone to convert naphthenes to aromatics and to form a total first vaporous product including unreacted hydrogen, unreacted feed and reacted products having a high concentration of acid wash color forming bodies in the 200° to 300° F. boiling range, reducing the temperature of the total first product to a temperature in the range between 500° F. and 700° F., immediately passing said total vaporous first product at said reduced temperature within a time in the range between 0.1 and 100 seconds after said total first product leaves said first zone into a second zone, hydrogenating said total first product in said second zone in the absence of extraneously added hydrogen in the presence of a hydrogenating catalyst selected from the group consisting of nickel-tungsten sulfide, platinum, Raney nickel, and cobalt molybdate at a temperature in the range between 550° F. and 700° F. and at a space velocity higher than a space velocity in said hydroforming step to form a second product having a low concentration of acid wash color forming bodies in the 200° to 300° F. boiling range and distilling said second product to recover a fraction boiling in the range between 200° and 300° F. having solvent properties and an acid wash color not in excess of 6.

6. A method in accordance with claim 5 in which the hydrogenation temperature is in the range between 600° and 650° F. and the hydrogenation liquid space velocity is in the range between 8 and 45 volumes of feed per volume of catalyst per hour.

7. A method for producing hydrocarbon solvents having a low acid wash color which comprises the steps of hydroforming a naphthenic hydrocarbon fraction containing a small amount of olefins less than about 2% by volume and boiling in the range between 200° and 300° F. under hydroforming conditions of temperature and pressure in a first zone to convert naphthenes to aromatics and to form a total first vaporous product including unreacted hydrogen, unreacted feed and reacted products having a high concentration of acid wash color forming bodies in the 200° to 300° F. boiling range, reducing the temperature of the total first product to a temperature in the range between 500° F. and 700° F., immediately passing said total vaporous first product at said reduced temperature within a time in the range between 1 second and 60 seconds after said total first product leaves said first zone into a second zone, hydrogenating said total first product in said second zone in the absence of extraneously added hydrogen in the presence of a nickel-tungsten sulfide catalyst at a temperature in the range between 550° F. and 700 F. and at a space velocity higher than a space velocity in said hydroforming step to form a second product having a low concentration of acid wash color forming bodies in the 200° to 300° F. boiling range and distilling said second product to recover a fraction boiling in the range between 200° and 300° F. having solvent properties and an acid wash color not in excess of 6.

8. A method for producing hydrocarbon solvents having a low acid wash color which comprises the steps of hydroforming a naphthenic hydrocarbon fraction containing less than about 2% by volume of olefins and boiling in the range between 200° and 300° F. at a temperature in the range between 850° and 1100° F. at a pressure in the range between 175 and 500 p. s. i. g. and at a space velocity in the range between 0.5 and 5.0 volumes of feed per volume of catalyst per hour in a first zone to convert naphthenes to aromatics and to form a total first product including unreacted hydrogen, unreacted feed and reacted products having a high concentration of acid
